UNITED STATES PATENT OFFICE.

JAMES L. BALLANTYNE, OF NEWTON, MASSACHUSETTS, ASSIGNOR TO THE NONANTUM WORSTED COMPANY, OF MASSACHUSETTS.

DABBING-BRUSH APPARATUS FOR COMBING-MACHINES.

SPECIFICATION forming part of Letters Patent No. 404,376, dated June 4, 1889.

Application filed October 19, 1888. Serial No. 288,600. (No model.)

To all whom it may concern:

Be it known that I, JAMES L. BALLANTYNE, a citizen of the United States, and a resident of Newton, in the county of Middlesex and State of Massachusetts, have invented new and useful Improvements in Dabbing-Brush Apparatus for Combing-Machines, of which the following, taken in connection with the accompanying drawings, is a specification.

10 This invention relates to improvements in dabbing apparatus for wool-combing machines for the purpose of giving the necessary reciprocating motion to the dabbing-brushes of such combing-machines and to 15 keep the working parts properly lubricated, as will hereinafter be more fully shown and described, reference being had to the accompanying drawings, where—

Figure 1 is a front elevation of the apparatus, showing the driving-pulley as removed. Fig. 2 is a central longitudinal section of the apparatus. Fig. 3 is an interior view of the device, the cover being shown as removed. Fig. 4 is a cross-section on the line X Y 25 shown in Fig. 1; and Fig. 5 is a side elevation drawn to a reduced scale, showing the manner in which my apparatus is driven.

Similar letters refer to similar parts wherever they occur on the different parts of the drawings.

1 represents the pillar of one of the small circular combs on a wool-combing machine, to which is secured in a suitable manner the box-bracket 2, said bracket being provided 35 with a bearing 3 for the cam-shaft 4, as shown in Figs. 2 and 4. In one piece with said shaft 4 is made the conical or tapering eccentric or cam, 5. (Shown in Figs. 2, 3, and 4.)

6 is the cover of the aforesaid box-bracket, 40 which is secured to the latter by means of the fastening-screws 7 7 and nuts 8 8, which also serve the purpose of securing to the front of the said cover 6 the gibbs 9 9, in which the front sliding plate 10 is guided.

45 The cover 6 has a bearing 12, in which the front end of the cam-shaft 4 is journaled, as shown in Figs. 1, 2, and 4.

13 is a screw-threaded gland surrounding the outer reduced end of the cam-shaft 4,

said gland being screwed into a central recess in the hub 12 and provided with a suitable packing, so as to prevent the escape of the lubricant at this place, as shown in Figs. 2 and 4.

14 is a grooved pulley secured, as usual, to the outer end of the shaft 4, which latter is rotated by means of a belt or cord 15, leading from the pulley 16 on the driving-shaft 17, as shown in Fig. 5.

18 is a detachable foot or bracket secured 60 to the lower end of the sliding plate 10, preferably by means of a screw 19, (shown in Figs. 1 and 2,) and to such foot or bracket is firmly secured the dabbing-brush 20, as shown in Figs. 1, 2, and 5. By having the foot-piece 65 18 detachable from the sliding plate 10, as shown, the dabbing-brush, when worn, can readily be removed from the sliding plate 10 and another one put in its place, and a brush may be taken from one machine and put on 70 another whenever so desired.

21 is a suitable packing secured between the meeting edges of the box-bracket 2 and the cover 6, so as to effect a tight joint between said parts to prevent escape of the 75 lubricant at such junction.

In the hollow space inclosed by the box-bracket 2 and cover 6 is located the cam-carrier 22, guided between vertical ribs 23 23 on the interior of the box-bracket 2, as shown in 80 Figs. 2, 3, and 4, said carrier having an upwardly-projecting stem 24, that passes through a perforation in the upper meeting edges of the box-bracket 2 and its cover 6, as shown in Figs. 2 and 3, and is there provided with a 85 screw-threaded gland 25, surrounding said stem and screwed into a recess in the upper part of the said box-bracket and cover, and provided with a suitable packing, as shown in Figs. 2 and 3, so as to effect a tight joint 90 at this place to prevent the escape of the lubricant.

The top and bottom faces of the carrier 22 are provided with hardened-steel faces 26 26, as shown in Figs. 2 and 3, against which the 95 cam or eccentric 5 acts during its rotation, said faces being preferably provided with horizontal projections 27 27, adapted to fit in

corresponding grooves in the interior of the carrier 22, as shown in Fig. 2. The said faces are preferably secured to the carrier 22 by means of screws shown in dotted lines in Fig. 5 3, or in any other suitable or equivalent manner. Said steel faces 26 26 may be replaced with new ones whenever worn out without the need of replacing the carrier 22, thus saving a great deal of expense in taking up the wear 10 on said carrier as may be needed from time to time.

To the upper end of the stem 24 is secured the hub 28, the forward end of which is provided with a screw-bolt 29 passing loosely 15 through a slot 30 in the upper end of the sliding plate 10, to which it is secured in an adjustable manner by means of the nut 31, as shown in Figs. 1 and 2.

It will be seen that by the rotation of the 20 shaft 4 and its cam or eccentric 5 a reciprocating motion is imparted to the carrier 22, the sliding plate 10, and the dabbing-brush 20, secured to it. The shaft 4 is longitudinally adjustable in its bearings in one end by 25 means of the regulating-screw 32, screwed through the rear end of the bearing 3, and in the other end by means of the stuffing-gland 13, as shown in Figs. 2 and 4, for the purpose of adjusting the tapering cam or eccentric 5 30 relative to the carrier 22 and its steel faces 26 26 so as to compensate for any wear that takes place on said cam and cam-faces.

The space between the interior of the box-bracket 2 and cover 6, in which the cam 5 and 35 carrier 22 are located, serves as a reservoir to contain the lubricant that is introduced into said chamber through a perforation 33 made in the upper portion of the box-bracket 2 or the cover 6, which perforation is normally 40 closed by means of a detachable screw 34, as shown in Figs. 1 and 3.

35 is another stop-screw screwed through a perforation 36 in the back of the box-bracket 2, or any other part of the walls inclosing the 45 oil-space, about on a level with the axis of the shaft 4, as shown in Fig. 3, so as to permit the oil-space to be filled to this level.

In charging the oil-chamber the screws 34 and 35 are removed and the oil is poured in 50 at the opening 33 until it commences to flow out through the opening 36, when the said 55 openings are closed by means of the respective screws 34 and 35 and remain in such closed positions as long as the device is in use. The lubricant being thus inclosed in the space 55 between the box-bracket 2 and its cover 6, all unnecessary waste of it is prevented and the device thus rendered self-lubricating.

On the interior of the box-bracket 2 and the 60 cover 6, near their upper ends, I have cast in one piece with said respective parts the curved ribs 37 37, which serve the purpose of arresting 65 the lubricant when splashed upward

during the upward stroke of the carrier 22, and thus preventing leakage of the lubricant 65 at the place where the spindle 24 passes through the stuffing-gland 25, as shown in Figs. 2 and 3. On the interior of the respective parts 2 and 6 are also made the curved ribs 38 38, which serve the purpose of conducting 70 the lubricant that has been splashed upward against the rib 37 to the outside of said ribs and down again to the lower part of the oil-reservoir, thus keeping the lubricant properly circulated therein and causing a proper 75 amount to be automatically fed to the moving parts within the reservoir. The peripheries of the box-bracket 2 and cover 6 being only provided with the intermediate packing 21, there will be a slight space or opening left between the abutting edges of the ribs 38, as shown in Fig. 4, through which the lubricant that is conducted from the top of the reservoir is gradually returned to the central and lower part of the said reservoir. Should such 80 packing, however, not be sufficient to leave the desired space between said ribs 38 38 for the purpose above mentioned, I may prefer to make in said ribs one or more recesses 39, adapted to conduct the lubricant from the upper to the lower part of the structure. It will thus be seen that the movable parts working within the space inclosed by the box-bracket and its cover are kept constantly lubricated and the escape of the lubricant is entirely 95 prevented, thus rendering the apparatus noiseless and economical in its use on account of its self-lubricating properties.

Having thus fully described the nature, construction, and operation of my invention, I 100 wish to secure by Letters Patent, and claim—

1. In a dabbing-brush apparatus, the box 2 and box-cover 6, and the cam-shaft 4, journaled in bearings in said parts and provided with the cam or eccentric 5, the carrier and its 105 sliding brush-carrying plate combined with the ribs 37 38 on the interior of said box and cover, substantially as and for the purpose set forth.

2. In a dabbing-brush apparatus, the box 2, 110 having bearing 3 and regulating-screw 32, and the cover 6, having stuffing-gland 13, combined with the rotary shaft 4, having the cam or eccentric 5, and the carrier 22, having upwardly-projecting spindle 24 guided in the upper 115 part of said box and cover and provided with a stuffing-gland 25, substantially as and for the purpose set forth.

In testimony whereof I have signed my name to this specification, in the presence of two subscribing witnesses, on this 10th day of October, A. D. 1888.

JAMES L. BALLANTYNE.
